UNITED STATES PATENT OFFICE

HAROLD G. RITCHIE, OF BATTLE CREEK, MICHIGAN, ASSIGNOR TO GAVIN RITCHIE
& SONS, INC., OF BATTLE CREEK, MICHIGAN

PRESSURE-REGULATING DEVICE

Application filed March 14, 1927. Serial No. 175,396.

The main objects of this invention are:

First, to provide an improved pressure regulating device for tire fillers and the like which is very accurate and may be quickly 5 adjusted to the desired pressure.

Second, to provide a pressure controlled valve which does not require a packing.

Third, to provide a device having these advantages which is simple and economical in 10 structure and not likely to get out of repair.

Objects pertaining to details and economies of my invention will definitely appear from the description to follow. The invention is defined in the claims.

15 A structure which is a preferred embodiment of my invention is clearly illustrated in the accompanying drawings forming a part of this application, in which:

Fig. 1 is a front elevation of an "air tower" 20 embodying the features of my invention.

Fig. 2 is a detail view mainly in vertical section on a line corresponding to line 2-2 of Figs. 1, 3 and 4.

Fig. 3 is a fragmentary view showing the 25 arrangement of the valve and its operating means within the air chamber or casing.

Fig. 4 is a diagrammatic view of the control means and its connections to the electromagnet.

30 Fig. 5 is an enlarged detail partially in section showing the arrangement of the valve and the operating connection of the armature of the electromagnet thereto.

Referring to the drawing, 1 represents the 35 pedestal of an "air tower", 2 the pivoted arm thereof and 3 the tire valve air chuck. These parts are shown conventionally and their details form no part of my invention.

40 In the embodiment illustrated I provide a housing 4 which is introduced into the pedestal or column 1 as a section or element thereof. This housing is open at one side and provided with a glass panel or window 5 which is secured in position by the flanged ring 6 fitting upon the housing. The housing is internally shouldered at 7 to support the dial 8, the spacing members 9 arranged between the dial and the window 5 constituting 45 nuts for the retaining screws 10. This

dial is graduated and provided with a pressure indicia as shown in Fig. 1.

Within the housing I mount an air chamber designated generally by the numeral 11 and which, in the embodiment illustrated, 55 comprises a rear section 12 secured to the rear wall of the housing by the screws 13, and a front section 14 which is secured to the rear section by the bolts 15. This housing is provided with an outlet pipe 16 to which 60 the air chuck 3 is connected.

The air supply connection 17 is connected to the air chamber as shown in Fig. 5, a needle valve 18 controlling this inlet connection. This needle valve seats outwardly 65 against the pressure in the conduit 17 and is held yieldingly upon its seat by means of the coiled spring 19 which is connected to the armature 20 of an electromagnet 21. This armature is pivoted at 22 and is provided 70 with an arm 23 engaging the valve, the arm carrying an adjustable screw 24 engaging the valve. The electromagnet, its armature and the valve are all arranged within the air chamber 11. This avoids the necessity of any 75 packing for the valve.

A Bourdon tube 25 is mounted on the projecting pipe 26 by which it is connected to the air chamber. This Bourdon tube is grounded in the air chamber walls through this connection. The Bourdon tube carries a contact 27 which is preferably threaded through the end of the tube to coact with the cam-shaped switch or control member 28.

This member 28 is mounted upon a spindle 29 provided with a finger piece 30 at its outer end so that it may be manually adjusted. This spindle carries an index finger 31 which is operatively associated with the dial 8, the cam and the index finger being properly positioned relative to each other so that the cam may be properly adjusted to set the device to the required pressure. A stop 32 is provided for the index finger so that it is stopped when returned to zero. The cam has 85 a recess 33 at the zero point so that when returned to zero the contact is broken. However, when moved from this zero position the contact 27 engages the cam and remains in engagement thereby closing the switch and 90 95 100

opening the valve until the pressure acting through the Bourdon tube member 25 breaks the contact and thereby opens the switch, allowing the valve to close.

5 The spindle is insulated from the housing and the air chamber as indicated, an electrical connection, however, being provided in the form of a disk 35 mounted on the spindle and the brush 36 mounted on the air chamber wall but insulated therefrom. This brush is connected to the electromagnet through the connection 37.

10 The power circuit indicated at 38 has one wire connected to the electromagnet 39 and the other grounded in the air chamber wall as indicated at 40. The connection to the Bourdon tube switch member 25 is through this ground connection as shown in Fig. 4.

15 In the operation of the device the finger piece 30 is manipulated to turn the pointer 31 to the indicia indicating the pressure desired. This rotates the control member 28 relative to the contact 27 bringing the control member into engagement with this contact member and thereby closing the circuit. The 20 air chuck 3 is then applied to the tire to be inflated. As soon as the required pressure has been reached the expansion of the Bourdon tube lifts the contact 27 from the control member 28, thereby breaking the circuit and closing the valve.

25 My improved pressure regulator is especially well adapted and designed by me for use in tire fillers, automatically closing the valve when a predetermined pressure is reached. It may be quickly adjusted to desired pressures and it is not necessary to return the index to zero after the device has been used, the valve automatically being 30 closed when the pressure in the line at the rear of the valve reaches a predetermined point.

35 By placing the valve and its operating parts within the air chamber I avoid the necessity of a packing for the valve.

40 45 While in the embodiment illustrated the inner end of the spindle is supported on the air chamber, I desire to point out that this is merely a matter of structural convenience.

Having thus described my invention what 50 I claim as new and desire to secure by Letters Patent is:

55 1. In a pressure regulating device, the combination of a housing, a dial therein provided with pressure indicating indicia, an air chamber within said housing provided with air inlet and outlet connections, a needle valve for the air inlet connection disposed within said air chamber and seating outwardly against the inlet pressure, an electromagnet 60 within said air chamber, a coacting armature pivotally mounted within said air chamber and provided with a return spring, said armature having an arm engaging said inlet valve whereby the valve is held yieldingly against 65 its seat, a spindle provided with a finger piece

and with an index finger operatively associated with said dial, a cam-shaped control member arranged on said spindle in relation corresponding to the said index finger, a Bourdon tube connected to said air chamber and arranged within said housing to embrace said control member, and a contact threaded for adjustment on said Bourdon tube coacting with said control member, said control member and Bourdon tube being electrically connected to and constituting a control switch for said electromagnet. 70 75

2. In a pressure regulating device, the combination of a housing, a dial therein provided with pressure indicating indicia, an air chamber within said housing provided with air inlet and outlet connections, a valve for the air inlet connection disposed within said air chamber, an electromagnet within said air chamber, a coacting armature pivotally mounted within said air chamber and provided with a return spring, said armature engaging said inlet valve whereby the valve is held yieldingly against its seat, a spindle provided with a finger piece and with an index finger operatively associated with said dial, a cam-shaped control member arranged on said spindle in relation corresponding to the said index finger, a Bourdon tube connected to said air chamber and arranged within said housing to embrace said control member, and a contact on said Bourdon tube coacting with said control member, said control member and Bourdon tube being electrically connected to and constituting a control switch for said electromagnet. 80 85 90 95 100

3. In a device of the class described, the combination of an air chamber provided with air inlet and outlet connections, a needle valve for the said air inlet connection disposed within said chamber and seating outwardly against the inlet pressure, an electromagnet within said air chamber, a coacting armature disposed within said air chamber and operatively connected to said valve, a spring acting to return said armature and yieldingly hold said valve on its seat, a Bourdon tube connected to said air chamber and provided with an adjustable contact, a cam-shaped control member operatively associated with said contact of said Bourdon tube, said Bourdon tube and control member being electrically connected to said electromagnet constituting a control switch therefor, a dial provided with pressure indicating indicia, and means for manually adjusting said control member provided with an index operatively associated with said dial. 105 110 115 120

4. In a device of the class described, the combination of an air chamber, a valve disposed within said chamber, an electromagnet within said air chamber, a coacting armature disposed within said air chamber and operatively connected to said valve, a Bourdon tube connected to said air chamber and provided 125 130 135

- with a contact, a cam-shaped control member operatively associated with said contact of said Bourdon tube, said Bourdon tube and control member being electrically connected to said electromagnet constituting a control switch therefor, a dial provided with pressure indicating indicia, and means for manually adjusting said control member provided with an index operatively associated with said dial. 5

5. In a device of the class described, the combination of an air chamber provided with air inlet and outlet connections, a needle valve for the said air inlet connection disposed within said chamber and seating outwardly 10 against the inlet pressure, an electromagnet within said air chamber, a coacting armature disposed within said air chamber and operatively connected to said valve, a spring acting to return said armature and yieldingly hold said valve on its seat, a Bourdon tube connected to said air chamber and provided with an adjustable contact, a cam-shaped control member operatively associated with said 15 contact of said Bourdon tube, said Bourdon tube and control member being electrically connected to said electromagnet constituting a control switch therefor, and means for 20 manually adjusting said control member. 25

6. In a device of the class described, the combination of an air chamber, a valve disposed within said chamber, an electromagnet within said air chamber, a coacting armature disposed within said air chamber and operatively connected to said valve, a Bourdon tube connected to said air chamber and provided with a contact, a cam-shaped control member operatively associated with said contact of said Bourdon tube, said Bourdon tube 30 and control member being electrically connected to said electromagnet constituting a control switch therefor, and means for manually adjusting said control member. 35

7. In a device of the class described, the combination of a housing, a dial therein provided with a pressure indicating indicia, an air chamber disposed within the housing, a valve for said air chamber arranged therein, an electro-magnet and coacting armature arranged within said air chamber, said armature being operatively connected to said valve, a Bourdon tube provided with a contact arranged within said housing and connected to said air chamber, a rotatable cam-shaped control member arranged within said 40 Bourdon tube to coact with its said contact, said Bourdon tube and control member being electrically connected to said electro-magnet and constituting a control switch therefor, and means for manually adjusting said control member from outside of said housing. 45

8. In a device of the class described, the combination of a housing, an air chamber 50
